INVENTOR:

William A. Brown.

BY

Spencer H. Van Banks.

ATTORNEYS.

UNITED STATES PATENT OFFICE.

WILLIAM ALLEN BROWN, OF PHILADELPHIA, PENNSYLVANIA.

EMERGENCY HEATER.

Application filed July 23, 1925. Serial No. 45,535.

My invention relates to the general class of emergency electric heaters which are usually bulky, unsightly, incommodious and unhandy, wherein I employ a small compact heater safely disposed, so that the fire hazard is reduced to a minimum and heat or light may be simultaneously or independently instantly applied to the room by the turn of a switch, my novel device being 10 screwed into the socket of any wall bracket, table or floor lamp, so as to complete any such bare fixture by making it immediately a heating and lighting fixture and which has the appearance to the casual observer of 15 an ordinary lighting fixture, since the heating element is disguised in such a manner that an entire house could be heated in ordinary weather by the disposition of a number of my novel devices throughout the different rooms and halls and in temperate climates no other means of heating would be required.

To the above ends, my invention consists of a novel and useful combination of a flue 25 or chimney surrounding an electric light bulb and heating unit set in a twin socket and combined with a threaded extension having a swivel attachment, so that the device may be screwed in any position, into 30 an ordinary electric bulb socket, my invention however, not being limited to a single electric bulb or heating unit, as I may employ a plurality of each or either in combination with one or more of the other, as is 35 evident.

For the purpose of illustrating my invention I have shown in the accompanying drawings forms thereof which are at present preferred by me, since they will give 40 in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a heating and lighting lamp embodying my invention, the section being taken on line 1—1, Figure 2, the flue or chimney only being shown in section and the rest of the figure shown in elevation.

Figure 2 represents a top plan view of 55 Figure 1.

Figure 3 represents a vertical sectional view of another arrangement of a heating and lighting lamp taken on line 3—3, Figure 4, the flue or chimney only being shown in section and the rest of the figure shown 60 in elevation.

Figure 4 represents a top plan view of Figure 3.

Figure 5 represents a top plan view of another arrangement of a heating and light- 65 ing lamp.

Figure 6 represents a vertical, sectional view of another embodiment of my invention.

Similar numerals of reference indicate 70 corresponding parts in all figures.

Referring to the drawings:—

1 designates the cylinder or chimney which also acts as a shade and is supported at the bottom by brackets 2, and at the 75 top by other brackets 3, which are held together by the bolt 4, said bolt being positioned so as to throw no line of shadow on the cylinder 1, which may be made of translucent qualities. The brackets 2 and 3 and 80 the retaining bolt 4 are attached to a common base 5, having two or more sockets 6, in which are screwed one or more electric light bulbs 7, of suitable candlepower and one or more heating elements 8, of suitable 85 wattage to heat the rooms or halls where the devices are to be placed, a single light and a single heating element being shown in Figures 1 and 2.

The heating element 8, shown herewith, 90 is applicable to any standard electric light bulb socket and has supporting arms 9, enclosing the same in any suitable manner which hold the element in an upright position when red-hot so that it will not touch 95 other integral parts of the device.

The base 5 is designed with a pendant swivel screw plug 10, having a knurled portion 11, so that the completely detachable heating and lighting lamp fixture may be 100 immediately installed in any position in any ordinary electric light bulb socket, and the various instrumentalities of my invention can be variously arranged so that the device may be applied to either upright 105 or inverted electric light bulb sockets.

The base 5 is further supplied with pull cord switches or any other suitable switch mechanism 12 which enables the user instantly to turn on the electricity supplying 110

the heating unit or the electric light bulbs, so that the device is capable of affording light and heat simultaneously or separately or independently as desired. If the heating element 8 should be of such large capacity as to interfere with the functioning of the electric light bulb by the generation of heat within the cylinder, a cylinder of mica or other fire-proof material 13 may be placed around the heating unit 8, or the electric light bulbs 7 or around both unit and bulbs as shown in Figures 3, 4, 5 and 6. In Figures 1 and 2, I have omitted said cylinder, but have shown the same in Figures 3 to 6, as surrounding the heating element, and it will be obvious that such a cylinder as 13 can be readily applied to the lamps. In Figures 1 and 2, I have shown a single lighting and heating element employed. In Figures 3 and 4, I have shown a plurality of lighting elements, and a single heating element positioned therebetween, the enclosing flue or casing 1, being more elongated than in Figure 2. In Figure 5, I have shown the flue 1 as substantially triangular in cross section.

In Figure 6 the arrangement admits of an ornamental outer shade 14 of the shape of a truncated cone, supported by the arms 16 and a mica or glass cylinder 13 around the heating unit 8. The lights 7 in Figure 5 are arranged in a pendent diverging position, with the central heating element above. It will be seen from the foregoing that it is possible to prepare ready for erection by any unskilled person, an artistic heating and lighting lamp that can be readily installed on any ordinary electric wall bracket or portable electric table or floor lighting fixture by merely screwing in the swiveled plug 10 and instantly light and heat may be applied to any part of a building where such sockets have been placed and connected.

In all the embodiments of my invention the common base 5, serves as a support for both the lighting and heating elements, and for the rod 4 which ties together the upper and lower brackets 2 and 3 or their equivalents, which support the outer shade.

As a heating device my lamp has the advantage over other devices of placing this dangerous apparatus in a safe position, out of the way of children and thoroughly guarded from curtains, papers and other inflammable articles which might be accidentally ignited. There is no unsightly electric stove standing about the floors, if a house is equipped with these devices, as it is masked behind an artistic fire-proof cylinder. The thermal action draws most of the atmosphere surrounding the device upwardly through the cylinder heating the room evenly and thoroughly.

It will now be apparent that I have de-

signed a new and useful combination of heating and lighting elements, which embodies the features of advantage enumerated as desirable, in the statement of the invention and the above description, and while I have in the present instance, shown and described, preferred embodiments thereof which will give in practice satisfactory and reliable results, it is to be understood that such embodiments are susceptible of modification in various particulars without departing from the spirit or scope of the invention, or sacrificing any of its advantages.

Having thus described my invention, what I claim as new and desire to secure by Letters Patent, is:—

1. In a detachable, heating, and lighting lamp, a vertical flue, a vertical heating unit and an electric light bulb positioned within said flue and so assembled as to give heat or light or both simultaneously or independently within the said flue, a base for said unit and bulb, and a plug pendent from said base.

2. In a detachable heating and lighting lamp, a base member, a vertical flue supported therefrom, a plurality of electric light bulbs and a vertical heating unit also supported from said base and controlled by pull switches so assembled as to give heat or light or both within the said flue, and a plug pendent from said base.

3. In a detachable heating and lighting lamp, a base, a vertical flue supported thereon, a vertical heating unit and electric light bulbs also supported from said base and so assembled as to give heat or light or both within said flue, a longitudinally extending guard for said heating element, and a plug pendent from said base.

4. A detachable heating and lighting lamp having vertical flues, vertical heating units and electric bulbs, an outer flue enclosing the two latter and so assembled as to give heat or light or both, a base supporting all the foregoing elements, and a plug pendent from said base.

5. In a detachable heating and lighting lamp, vertical flues, vertical heating units and surrounded thereby electric light bulbs also surrounded by vertical flues so assembled and controlled by switches as to give heat or light or both, a base for said units and bulbs, and a plug pendent from said base.

6. In a detachable heating and lighting lamp, vertical flues, vertical heating units surrounded thereby, electric light bulbs, vertical flues surrounding the latter, an outer shade, switches for said units and bulbs so as to give heat or light or both, a base common to said units, bulbs and shade, a plug pendent from said base.

7. In a device of the character stated, a base, a heating and lighting element supported therefrom, supporting arms for said

- heating element also supported from said base, an outer shade enclosing said elements, a bracket common to said base and the lower portion of said shade, an upright rod supported on said base, an upper bracket common to the upper end of said rod and the top of said shade, and a plug pendent from said base.
8. In a device of the character stated, a base, a heating and lighting element supported therefrom, a rod on said base, supporting arms for said heating element also supported from said base, an outer shade enclosing said elements, a bracket common to said base, and an upper bracket common to the upper end of said rod and the top of
- said shade in combination with a pendent plug depending from said base.
9. In a device of the character stated, a base, a heating and lighting element supported therefrom, supporting arms for said heating element also supported from said base, an outer shade enclosing said elements, a bracket common to said base and the lower portion of said shade, an upright rod supported on said base, and an upper bracket common to the upper end of said rod and the top of said shade in combination with a pendent screw plug depending from said base having a knurled portion intermediate said plug and base.

WILLIAM ALLEN BROWN.
